UNITED STATES PATENT OFFICE.

WILLIAM F. TREIBER, OF CORNING, NEW YORK, ASSIGNOR TO INGERSOLL-RAND COMPANY, OF NEW YORK, N. Y., A CORPORATION OF NEW JERSEY.

UNLOADING DEVICE FOR COMPRESSORS.

1,093,299.

Specification of Letters Patent. Patented Apr. 14, 1914.

Application filed May 16, 1912. Serial No. 697,708.

To all whom it may concern:

Be it known that I, WILLIAM F. TREIBER, a citizen of the United States, residing in Corning, in the State of New York, have 5 invented certain new and useful Improvements in Unloading Devices for Compressors, of which the following is a specification.

This invention relates to unloading devices for air or gas compressors and more 10 particularly to the type of unloaders which are used in connection with constantly operating compressors for reducing the load on the compressor when the pressure in the receiver or discharge line reaches a certain 15 predetermined amount.

In compressors as heretofore used this reduction of the load has been generally accomplished by closing the intake of the compressor thus causing the compressor piston 20 or pistons to operate in a medium of a more or less reduced pressure. This has the effect of reducing the load to possibly one-third of the full load in practical operation and can not be carried much lower than this without 25 excessive precautions against leakage.

The object of the present invention is to provide a practical means whereby the load in the compressor can be reduced below the practical limits of such an unloader as above 30 described and this has been accomplished by providing an automatic means, operating in connection with an intake closing controller, for unloading the discharge line of the compressor to atmosphere.

35 A practical embodiment of my invention is shown in the accompanying drawings in which—

Figure 1 is a side elevation of a compressor and a receiver, and an unloading device embodying my invention in connection therewith. Fig. 2 is a section through the intake closing valve and the auxiliary valve controlling its action drawn to different scales and Fig. 3 is a section through the 45 unloader for the discharge line.

The compressor system as shown comprises a two-stage compressor with cylinders 1 and 2, air or other gas being taken into the compressor by a pipe 3 and discharged through the discharge pipe 4 into the receiver 5. From the receiver 5 a pipe 6 runs to a water and dirt collector 7 of ordinary construction which forms no part

of the present invention. From the water and dirt collector 7 two small pipes 8 and 9 55 lead to an auxiliary valve 10 the details of which likewise form no part of the present invention. Pipe 9 leads to a chamber 11 in the auxiliary valve 10 admitting receiver pressure to the surface of the diaphragm 12 which, at a pressure predetermined by the tension of the spring 13, uncovers the opening of passage 14 and allows fluid at receiver pressure to enter the chamber 15 forcing over the diaphragm 16 and 60 the valve 17 connected therewith and opening communication from the pipe 8, containing fluid at receiver pressure, to the pipe 18. When the valve 17 is in its normal position pipe 18 is in communication with 70 a passage 17^a which leads either to atmosphere, in an air compressor, or in a gas compressor by a pipe (not shown) to the compressor intake.

The pipe 18 leads to the lower side of the 75 piston 19 moving in the cylinder 20. The head of the piston 19 is provided with a valve disk 21 which is adapted to be forced by fluid pressure back of piston 19 against the valve seat 22 closing the inlet pipe 3 of 80 the compressor. The pipe 18 leads also to a discharge line unloader 23 which is of novel construction. This discharge line unloader consists of a casing 24 which is divided into three chambers 25, 26 and 27. 85 Chamber 25 is in free communication with the receiver 5 through the pipe 28, chamber 26 is in free communication with the discharge pipe 4 from the compressor, and chamber 27 is in free communication with 90 the atmosphere through the opening 29.

Seating in the partition between the chambers 25 and 26 are twin valves 30 and 31 which control the passage of the compressed fluid from the compressor to the 95 receiver. The bodies of these valves are hollow and form cylinders which slide on stationary piston plugs 32 and 33 threaded into the casing, these piston plugs being provided with inlet passages 34 and 35 100 leading to the heads of the pistons and communicating with pipe 18 through 36 and 37. Light springs 38 and 39 are provided to exert a small pressure on the valves 30 and 31 tending to close them. These valves 105 are in the nature of check valves in that

when closed they prevent the return of fluid from the receiver into the discharge line, and seat in such a position that when seated they are held closed by the pressure in the receiver. It is evident that a simple check valve could be used here, but such a valve, though operative offers a certain resistance to the passage of the fluid under normal running conditions, while the present valve remains open under such conditions only becoming a check valve when required.

Seated in bushings 40 and 41 in the partition between the chambers 26 and 27 and opening inwardly into the chamber 27 are twin discharge valves 42 and 43. Shanks 44 and 45 extend upwardly from the valve 42 and are provided, at their upper end, with nuts 46 and 47 against which press springs 48 and 49 tending to hold the valves 42 and 43 in closed position. Sliding in cylinders 50 and 51 are pistons 52 and 53 which are cup shaped and have on their interior surfaces projecting lugs 54 and 55 which contact with the ends of the valve shanks 44 and 45. The cylinders 50 and 51 are in communication with the pipe 18 through the pipes 56 and 57.

As stated above the chamber 27 is in communication with the atmosphere through the opening 29. If the gas being compressed is other than air a pipe (not shown) connects the opening 29 with the inlet of the compressor.

In operation, when the pressure in the receiver reaches a point which is determined by the pressure of the spring 13 in the auxiliary valve 10, the valve 17 is thrown, opening the pipe 18 to receiver pressure, the air or gas under pressure passing through the pipe 18 and pipes 36 and 37 to the interior of the valves 30 and 31 balancing the discharge line pressure on the faces of the valves and allowing the springs 38 and 39 to force them to a closed position. Under ordinary running conditions the pipe 18 and consequently the interior of the valves 30 and 31 are in communication with the atmosphere and the pressure in the discharge line acting against the faces of these valves, holds them in a fully open position, overcoming the pressure of the springs 38 and 39. Simultaneously with the passage of the air or gas into the valves 30 and 31 closing them, air or gas flows into the cylinders 50 and 51 forcing up the pistons 52 and 53 and consequently raising the valves 42 and 43 establishes free communication between chambers 26 and 27 thus allowing air or gas coming from the outlet of the compressor to be discharged either to the atmosphere through the pipe 29, when air is being pumped or to the inlet of the compressor if gas is being compressed. At the same time air or gas under pressure in the

pipe 18 flows into the back of the cylinder 20 raising the piston 19 and forcing the valve disk 21 therein against its seat 22 thus closing off the intake of the compressor. When the pressure in the receiver falls again below the pressure for which the auxiliary valve 10 is set the valve 17 therein will return it to its original position allowing the air or gas under pressure in the pipe 18 and consequently that air or gas in the valves 30 and 31, tending to hold them closed and in the cylinders 50 and 51 holding the valves 42 and 43 open and in cylinder 20 holding the valve 21 closed, will be released and escape through the passage 17^a either to atmosphere in the case of air or to the compressor intake in the case of gas.

It will be readily understood that by the use of my unloading system the load in the compressor can be reduced to a very small percentage of the full load enabling the compressor to be run with very little power when unloaded thus saving a considerable amount of power otherwise wasted, when the compressor is run under no load for any length of time. As stated above when the compressor is unloaded only by choking the intake, the considerable amount of air or gas which is impossible, from a practical point of view, to prevent being passed through the compressor, must be forced into the discharge line of the compressor against the back pressure of the receiver. By applying however a system of valves which open the discharge line to atmospheric pressure at the same time the intake is closed, the only work done by the compressor is expended in forcing a small amount of air or gas which leaks in through the intake or other openings in the compressor through the compressor and out again to a medium at atmospheric pressure. As a result great economy of power can be secured without resorting to precautions against leakage, etc., which are impracticable from a commercial point of view.

Although in the drawings a single auxiliary valve is shown controlling both the intake unloader and the discharge line unloader it is evident that a separate auxiliary valve could be used for operating each unloader as the function of this valve is merely to allow the passage of air or gas to the unloaders at a definite and predetermined point of receiver pressure. It would also be possible without invention to devise other methods of operating the two unloaders simultaneously or serially when the predetermined receiver pressure is reached and such modifications are considered to be within the spirit and scope of the invention as expressed in the claims as are also modifications in the form of the specific means shown.

What I claim is:

1. In combination, a fluid compressor, a

receiver, a discharge line connecting said compressor and said receiver, a valve for closing the intake of the compressor, an unloader in said discharge line comprising a check valve mechanism and a discharge valve between said check valve mechanism and said compressor, pistons operating said intake closing valve and said discharge valve, cylinders for said pistons and auxiliary valve mechanism for connecting said cylinders with fluid under pressure when the receiver pressure reaches a predetermined amount, and with fluid at atmospheric pressure when the receiver pressure falls below a predetermined amount.

2. In combination, a fluid compressor, a receiver, a discharge line connecting said compressor and said receiver, an unloader in said discharge line comprising a line closing valve, a discharge valve, means for positively closing the line closing valve by means of fluid pressure, and means for opening the discharge valve to unload the compressor outlet to atmospheric pressure by fluid pressure, and auxiliary valve mechanism to supply fluid pressure to operate said line closing

valve and said discharge valve at a predetermined pressure in said receiver.

3. In an unloading device for compressors, a discharge line unloader comprising a valve having a valve face and a hollow body, a stationary piston plug in said body, said body sliding thereon, a fluid inlet passage through said piston plug, a discharge valve, a stem on said valve, a piston engaging said stem, a cylinder for said piston and means for admitting fluid under pressure to said inlet passage and said discharge valve cylinder.

4. In an unloading device for compressors, a discharge line unloader comprising a line closing valve, means including a cylinder and piston for positively closing said line closing valve, a discharge valve, means for operating said discharge valve including a cylinder and piston and means for supplying fluid to said cylinders to operate said valves.
